UNITED STATES PATENT OFFICE.

THOMAS J. STEARNS, OF BOSTON, MASSACHUSETTS, ASSIGNOR TO ROXBURY CARPET COMPANY, OF SAME PLACE.

DESIGN FOR CARPET.

Specification forming part of Design No. 11,222, dated June 3, 1879; application filed April 30, 1879.
[Term of patent 3½ years.]

To all whom it may concern:

Be it known that I, THOMAS J. STEARNS, of Boston, in the county of Suffolk and State of Massachusetts, have invented a new and original Design for Carpets, of which the following is a specification.

The nature of my design is fully illustrated in the accompanying photographic illustration, forming a part of this specification.

The prominent features of the design are, the main figure or shield A, having parallel sides and curved ends, and the rectangular figure 1, placed diagonally of the pattern. The figures A and 1 alternate with each other through the center of the pattern. The figure A has a bouquet nearly covering it, as shown. B C D are ornamented curved shields or figures at the corners of the main figure A. The figure C has a bouquet above it. E is a rectangular diagonal figure, which is partially covered by a corner of the figure A. 6 is a rectangular transverse figure above the figure A, and partially overlapped thereby and by the figure E. The figures B, C, D, E, and 6 are ornaments or accessories of the main figure A. 2 and 3 are fan-shaped figures at opposite corners of the figure 1. 4 4 are rectangular figures at opposite sides of the figure 1. 5 is a rectangular figure on another side of the main figure 1. The figures 2, 3, 4, and 5, are ornaments or accessories of the figure 1.

I claim—

1. The design for a carpet having the figures A and 1, alternating through the center of the pattern.
2. The design for a carpet having the figures A B C-D.
3. The design for a carpet having the figures A, B, C, D, E, and 6.
4. The design for a carpet having the figures 1, 2, and 3.
5. The design for a carpet having the figures 1, 2, 3, 4 4, and 5.
6. The design for a carpet having the figures A and 1 and their accessories, as set forth.

In testimony whereof I have signed my name to this specification in the presence of two subscribing witnesses this 26th day of April, 1879.

THOMAS J. STEARNS.
